UNITED STATES PATENT OFFICE.

HARRY F. GEIST, OF RACINE, WISCONSIN.

MAGNETO.

1,334,298.

Specification of Letters Patent. Patented Mar. 23, 1920.

Application filed January 8, 1917. Serial No. 141,230.

To all whom it may concern:

Be it known that I, HARRY F. GEIST, a citizen of the United States, and resident of Racine, in the county of Racine and State of Wisconsin, have invented new and useful Improvements in Magnetos, of which the following is a description, reference being had to the accompanying drawings, which are a part of this specification.

10 The invention relates to magnetos for ignition purposes.

The invention is more particularly designed to provide a magneto of the armature wound type in which by reason of the construction of the field pole shoes and the armature a magneto of efficient magnetic and electrical properties is obtained.

The invention is further designed to provide a magneto of the armature wound type 20 which may be readily assembled or taken apart due to the simplicity of its construction and the arrangement of its parts.

The invention further consists in the several features hereinafter set forth and more particularly defined by claims at the conclusion hereof.

In the drawings:

Figure 1 is a front view of the device, part of the interrupter adjusting lever being broken away;

Fig. 2 is a section taken on the line 2—2 of Fig. 1, parts being broken away;

Fig. 3 is a section taken on the line 3—3 of Fig. 2;

Fig. 4 is a section taken on the line 4—4 of Fig. 1;

Fig. 5 is a section taken on the line 5—5 of Fig. 1;

Fig. 6 is a diagrammatic view of the electrical circuit.

For convenience in explanation the mechanical construction of the frame, field, armature, and interrupter will be described first and the circuit connections of the machine together with its operation thereafter.

The frame consists of the portion 10 having a base 11 adapted to be mounted on any suitable support adjacent to the engine to which the magneto is operatively connected.

50 The field consists of pole shoes designated as a whole as 12 and permanent magnets 13 connected to said pole shoes and the frame 10 by metal strips 14 surrounding said magnets and connected at their lower ends to the frame 10 by any suitable means, such as screws 15.

The pole shoes are of special construction

so as to reduce the iron losses due to eddy currents as much as possible and to reduce the time constant of the secondary winding. 60 These pole shoes consist of a plurality of soft iron laminæ 16 clamped between solid iron or steel blocks 17 by means of rivets 18, both the laminæ and the blocks contacting with the magnets and having their inner 65 sides curved to accommodate the armature, as shown in Fig. 3. The laminæ 16 used in the field serve to break up the eddy currents which travel through the field at right angles to the plane of said laminæ and thus reduce 70 the iron losses in the field. Holes or recesses 19 are provided in the blocks 17 to reduce the coefficient of self induction of the secondary winding and by so doing reduce the time constant of the secondary winding. For 75 convenience in manufacture the frame 10 is cast around the laminæ 16 and blocks 17 by a die-casting method so that the whole forms one unitary structure having the bore 20 therein for receiving the armature and 80 its bearings.

The armature consists of an I-shaped core formed by I-shaped soft iron laminæ 21 secured by rivets 22 to I-shaped solid iron pieces 23 having extensions 24 and 25 85 shaped to correspond to the upper and lower curved ends of the I-shaped core and further secured by rivets 26 to form an integral core and further consists of the armature windings hereinafter described. The laminæ are provided in the core to reduce the iron losses by breaking up the eddy currents set up therem. The solid iron blocks of the core are provided with holes 27 to reduce the coefficient of self induction of the secondary 90 winding to thereby reduce the time constant of the secondary winding. It will be noted from Fig. 3 that the ends of the core overlap the ends of the pole pieces, just before the break in the magnetic field is made and 100 when the web of the I is disposed at right angles to the pole pieces the magnetic flux will be the greatest.

The armature windings comprise a primary coil 28 which is insulated from the core 105 by insulation 29 and a secondary coil 30 insulated from the primary and from the core, both coils being wound around the web portion of the I-shaped core, the primary being grounded to the core by having one end (not shown) connected to a grounding screw 31 as is usual in devices of this kind.

The armature is provided with brass or

other non-magnetic end plates 32 and 33 suitably secured thereto, the plate 32 having the armature shaft 34 fixedly mounted therein and the plate 33 having a metal bushing 35 fixedly mounted therein. The shaft 34 is journaled in a ball bearing journal 36 mounted on a frame end plate 37 secured to the frame 10 and through which the shaft extends, the shaft being connected up to any suitable source of power for rotating it, as by a gear connection with the engine and the bushing 35 is journaled in a ball bearing journal 39 mounted on a frame end plate 40 secured to the frame 10 by screws 41, the end plate 37 being secured in a similar manner. On the removal of the end plates 37 and 40, the whole armature may be withdrawn from the frame.

The primary circuit is also provided with a condenser 42 mounted in the armature on the plate 33 by means of a threaded plate 43 and bolt 44 which also serves to secure the interrupter in position as hereinafter described, the condenser being insulated from the conductor parts by a plate 45 and bushing 46 of insulating material.

The interrupter consists of a metal disk 47 having a tapered projection 48 seated and keyed in a tapered seat 49 of the bushing 35 and having mounted thereon but insulated therefrom a contact carrying member 50, the bolt 44 passing through apertures in the member 50 and the disk to clamp said parts to said bushing together with the condenser 42, the bolt being insulated from the disk 47. A contact lever 51 is pivotally mounted on a bushing 51' of insulating material on a stud screw 52 secured to the disk 47 and is provided with a contact point 53 adapted to engage with an adjustable contact 54 mounted in the member 50. The contacts 53 and 54 are normally held together by means of a spring 55 secured to the lever 51 and to the disk 47 and the circuit is interrupted by breaking the contact by means of a cam 56 carried on an adjustable sleeve 57 mounted on a cylindrical boss 58 of the end plate 40 and provided with an operating lever 59, said cam adapted to contact with a cam block 60 on the lever 51, during the rotation of said lever with the armature, the part of the lever 51 carrying the block 60 moving inwardly while in contact with the cam 56 and the other end of the lever carrying the contact 53 moving outwardly to break the circuit.

Means are also provided for collecting the current from the armature consisting of a collector ring 61 mounted in an annular groove of a disk 62 of insulating material which is mounted on the armature shaft 34, the ring being connected to the secondary coil by an insulated conductor wire 63, passing through an insulating boss on spool

62 through end plate 32. A contact finger 64 yieldingly slidably mounted in a binding post 65 contacts with the ring 61, the post 65 and finger 64 being insulated from the frame by a socket member 66 of insulating material. The contact finger 64 is adapted to be connected with the ungrounded terminal of the spark plug 67.

A circuit wire 68 connects the primary coil with one side of the condenser and thence to the insulated interrupter point through bolt 44, and a circuit wire 69 grounds the other side of the condenser to the armature core, while the interrupter spring 55 grounds the interrupter and short circuits the primary winding and the condenser when the points 53 and 54 are in contact. The discharge brush 70 grounds the armature to the frame and prevents the secondary current from passing through the oil in the ball bearings.

It will be noted in the present construction that the laminated part of the armature is disposed in line with the laminated part of the field and that the solid iron blocks on the field extend the length of the armature core on either side.

In Fig. 6 I have shown diagrammatically the circuit connections between the primary secondary coils, the condenser, interrupter, spark plug and the ground. It will be noted that the primary winding is connected in series with the interrupter and is grounded on the core. The condenser is shunted across the primary circuit, one side being connected to primary circuit by the wire 68 and the other side being grounded on the core by the wire 69. One side of the secondary coil is connected to the primary and the other end of this coil is connected to the ungrounded electrode of the spark plug 67 through the wire 63, ring 61, finger 64, post 65 and the wire (not shown) leading from said post to the aforementioned electrode of the spark plug.

The operation of the device is as follows: When the armature is rotated by the shaft 34 so as to move the core at right angles to the position shown in Fig. 3, all the magnetic flux is then directed through the pole pieces. After the armature has moved past the position shown in Fig. 3 and just as the ends of the armature leave the ends of the pole pieces, the cam is set by the lever 59 to move the lever 51 to open the primary circuit at the interrupter contacts. When this occurs, the current, that is generated due to the electrical short circuit of the primary through the interrupter contact points under the assumed armature motion, is suddenly checked, and the reactive flux and its distorting effect upon the excitation flux, which represent the stored electro-magnetic energy simultaneous and coincident to the current, must also suddenly disappear. It

disappears from the primary and because of the mutual inductance is absorbed by the secondary circuit where it is expended in the form of an ignition spark at the spark 5 plug electrodes.

The function of the condenser is to quicken the rate of the speed at which the magnetic shift takes place, thereby aiding very materially in the energy transfer. It 10 also protects the interrupter contact points from arcing at the time of break.

The distinctive pole piece and armature constructions are important in producing a successful machine as the soft iron laminæ 15 reduce the iron losses and the holes in the solid iron parts of the pole pieces and the armature core reduce the time constant of secondary winding so that an improved transformation of energy takes place between the primary and secondary circuits. 20

The reason for iron losses in the pole pieces is due to the fact that, on the closed circuit of the primary, the current set up in the primary sets up a reactive flux that 25 crowds the main flux of the magnets to the edge of the pole piece from which the armature is passing, and when the interrupter opens and the reactive flux suddenly disappears, the main flux takes its natural path 30 which is then through the other edge of the pole piece. The sudden change from one edge to the other sets up eddy currents in the pole pieces that flow parallel to the axis of rotation of the machine and by using 35 laminæ disposed at right angles to this path the eddy current losses are reduced. While the construction herein shows both laminæ and solid iron combined together, the laminations of the pole pieces are placed directly 40 opposite the laminations of the armature and thus take care of the greater part of the flux.

In this type of machine the energy is generated and stored in the form of a distorted 45 magnetic field during the period that the primary circuit is closed through the breaker and at that time the secondary is idle. On the interruption of the primary by the breaker a transformation of energy 50 occurs during which the energy passes from the primary to the secondary circuit. In order that the transformation be as perfect as possible, the time constant, that is the time it takes energy to either build up or 55 die down in the circuit, of the secondary must not be greater than that of the primary in connection with its condenser. To reduce the time constant of the secondary and have it equal to that of the primary 60 I have provided the recesses 19 in the solid iron pieces 17 of the field and the holes 27 in the armature core.

The advantages of having a secondary circuit with the proper time constant is not

only the fact that more energy will enter 65 the spark but that the size of the condenser necessary will be reduced, a cleaner action at the breaker points will result and the number of turns of wire required in the secondary coil will be reduced. 70

It will be seen that certain of the features of construction of this invention may be used in the low tension form of magneto where the armature carries only one coil and no condenser in which case the 75 apertures in the armature and field would be omitted.

I am aware that the specific construction herein described, is subject to modification and change and I therefore desire it to be 80 understood that such modifications and changes as come within the scope of the appended claims are within the spirit of my invention.

What I claim as my invention is:

85

1. In a wound armature type magneto, the combination of a revoluble armature carrying primary and secondary coils, a field structure comprising a frame, field magnets and pole pieces, said pole pieces including solid iron blocks having apertures 90 therein to reduce the time constant of the secondary, substantially as described.

2. In a wound armature type magneto, the combination with a field structure, of a revoluble armature including primary and secondary coils and a core, said core including solid iron parts having apertures 95 therein to reduce the time constant of the secondary, substantially as described. 100

3. In a wound armature type magneto, the combination of a revoluble armature including primary and secondary coils and a core including solid iron parts having apertures 105 therein for reducing the time constant of the secondary circuit and a field structure comprising a frame, field magnets and pole pieces including solid iron parts having apertures therein for reducing the time constant of the secondary circuit. 110

4. In a wound armature type magneto, the combination of a revoluble armature comprising primary and secondary coils, wound parallel to its axis, and a core comprising connected together soft iron laminæ disposed at right angles to the armature and solid iron parts having apertures therein for the purpose described, and a field structure comprising a frame, field magnets, and pole pieces, said pole pieces consisting of connected together soft iron laminæ disposed at right angles to the axis of rotation of the armature and opposite to the laminated portion of the core and solid iron blocks having apertures therein. 115 120 125

In testimony whereof, I affix my signature.

HARRY F. GEIST,
